Patented Mar. 12, 1912.

UNITED STATES PATENT OFFICE.

CARL F. LUNDEBERG, OF HARTFORD, CONNECTICUT, ASSIGNOR TO UNDERWOOD TYPE-WRITER COMPANY, OF NEW YORK, N. Y., A CORPORATION OF NEW JERSEY.

TYPE-WRITING MACHINE.

1,019,978.

Specification of Letters Patent. Patented Mar. 12, 1912.

Application filed March 17, 1910. Serial No. 549,909.

To all whom it may concern:

Be it known that I, CARL F. LUNDEBERG, a citizen of the United States, residing in Hartford, in the county of Hartford and 6 State of Connecticut, have invented certain new and useful Improvements in Type-Writing Machines, of which the following is a specification.

This invention relates to keys for type-writing and other machines, and more particularly to the tabulating keys of type-writing machines, wherein it is desired to change the denominations of the keys.

The object of the invention is to provide 15 improved and simplified means to enable a wide range of key denominations or designations to be used, and to afford more room on the keys for the display of such designations, and therefore, permit the characters 20 to be enlarged in size. To these ends, the key has an indicator bar or shaft journaled to turn over therein, said bar having a number or other sign on each of two or more of its sides.

25 In the accompanying drawings, Figure 1 is a perspective view of a key equipped with my invention and partly broken away to better show the construction. Fig. 2 is a part sectional view, showing the indicator shaft in normal position. Fig. 3 is a similar view, showing the indicator shaft partially rotated. Fig. 4 is a perspective view 30 of the component parts of the key disassembled. Fig. 5 is a diagrammatic view showing the connection between the key and a 35 denomination stop. Fig. 6 is a diagrammatic plan view showing in the upper row a set of denomination keys, of which the first four are of ordinary construction, and the last six are constructed in accordance with 40 the invention. Upon these six keys the movable indicators are shown. The second row illustrates the same six keys, the indicators having been rotated so that the 45 keys may be used for different denominations. When adjusted according to the upper row, the ten keys and their stops are adapted for denominational work up to millions, with punctuation marks between the 50 hundreds and thousands, and also between the hundreds of thousands and millions. In the lower row, the punctuation marks are omitted and the capacity of the machine is increased to hundreds of millions. Fig. 7

is a detail perspective view of the indicator 55 shaft, showing the other two side faces from those shown in the detail view in Fig. 4.

The key is illustrated as mounted upon the usual lever 2 which is connected to a rod 60 3 having at its upper end a denomination stop 4 to coöperate with a column stop 5 carried upon a rack or bar 6 mounted upon the usual carriage (not shown). The key comprises a base or seat 7 on which is mounted 65 a cap 8 in the form of a ferrule, having ears 9 to catch under the seat. The cap has a rim 10 around its upper edge turned over upon a transparent cover or glass plate 11, superposed upon a shutter 12 having openings 13. The shutter rests upon an annular shoulder 14 formed in a stationary ring or annular body or barrel 15 seated on the base 7 and inclosed within the cap 8, said shutter having nibs 16 fitted into recesses 17 75 in the upper edge of the ring to hold the shutter stationary.

The space between the shutter 12 and seat 7 constitutes a chamber within the key, in which is located a character-bearing device 80 comprising an indicator shaft 18, having a plurality of faced sides, upon which the characters are applied, different faces or sides bearing different characters. The opposite reduced ends 25 of said shaft or bar 85 are rotatable in opposite elongated guide-slots or bearings 19 formed in the walls of the ring 15, and the shaft turns over in the key, on an axis parallel to the face of the key. An indicator bar having more than 90 two faces can be used, and consequent increase in the number of designations for each key is obtained. Moreover, by arranging the shaft to turn over on an axis parallel with the face of the key, the characters on 95 the shaft may be made larger than practicable heretofore on character-bearing disks which rotated in plates parallel with the faces of the keys; and larger sight openings can be made in the shutters. Other advantages are also apparent, as for instance, four changes can be made upon each key.

In the example shown in Figs. 2, 3 and 4, one face of the indicator bears the characters "1 T," meaning one thousand, and another 105 face bears the characters "10 T," meaning ten thousand. The former characters, preferably, lie at right angles to the latter, so

that a quarter-turn of the indicator, made by means of a finger piece 20 secured to one end of the shaft which projects through an opening 21, in the wall of the cap 8, causes 5 "10 T" to become hidden and "1 T" to be brought into view. Fig. 7 shows the remaining two sides of the indicator, bearing characters corresponding to those used in the English monetary system. The shaft may be 10 provided with either more or less sides than the four indicated in the drawings, and the characters may be applied to all the faces or to a less number, as desired. The finger piece may project from either side or at the 15 rear of the key, as is most convenient. Said shaft is yieldingly supported by a compression spring 22, resting on the seat 7, the ends of which spring are crossed, as at 23, to form a crotchet or bearing for the indicator 20 shaft, which is annularly grooved intermediate its ends, to form a neck, as at 24, to allow the spring fingers to clasp and hold the shaft up.

One or another of the faces of the indicator is normally pressed up against the closed end of the cap by the spring 22, to prevent accidental rotation of the indicator shaft. The characters register with the openings 13 in the shutter. When the indicator 25 is turned over to change the key denomination, the uppermost face operates as a cam against the under surface of the shutter, to force the indicator downwardly in its slots 19, and opening 21, against the tension 30 of the spring 22, as shown in Fig. 8, during the first half of its quarter-revolution; the spring forcing the indicator back to normal position, shown in Figs. 1 and 2, during the latter half of the quarter revolution.

40 The shoulders 26 formed at the juncture of the body of the indicator and its reduced ends contact with the opposite sides of the ring 15 to prevent endwise displacement of the indicator.

45 Variations may be resorted to within the scope of the invention, and portions of the improvements may be used without others.

Having thus described my invention, I claim:

50 1. A key having a character-bearing device inclosed therewithin, and turning on an axis substantially parallel to the face of the key, and having a finger-piece exterior to the key whereby the character-bearing device 55 may be rotated.

2. A key having a character-bearing device inclosed therewithin, and turning on an axis substantially parallel to the face of the key, and having a finger-piece exterior to the key whereby the character-bearing device 60 may be rotated, and a detent to hold said device in adjusted position.

3. A key provided with a seat, a cap, a character-bearing device journaled in the 65 cap, and turning on an axis substantially

parallel with the face of the key, one end of said device extending through an aperture in the cap to facilitate turning, and a detent to hold the device in adjusted position.

4. A key comprising a cap, means for closing one end of the cap to form the face of the key, a character bearing device journaled within the cap and capable of movement toward and from the face of the key, the character-bearing device having flat faces carrying the characters, and a spring to normally press one or another of the flat faces against the face of the key to prevent accidental turning of the character-bearing device. 70

5. A key comprising a cap, means for closing one end of the cap to form the face of the key, a character-bearing device journaled within the cap and capable of movement toward and from the face of the key, the character-bearing device having flat faces carrying the characters, and a spring to normally press one or another of the flat faces against the face of the key to prevent accidental turning of the character-bearing device, 75 80 one end of the character-bearing device extending through an opening in the cap and a finger-piece secured to such end to turn the device.

6. A key having a cap closed at one end to form the face of the key, an indicator shaft journaled within the cap and having flat faces bearing different characters, and yielding means to press one or another of the flat faces against the face of the key to hold the indicator in adjusted position. 90

7. A key having a cap closed at one end to form the face of the key, an indicator loosely journaled within the cap to move toward and from the closed end thereof, and 105 to turn relative thereto, the indicator having faces bearing different characters, a spring to press one or another of the faces against the closed end of the cap to prevent accidental rotation of the indicator, the flat faces being effective by their contact with the closed end when turning to cam the shaft away from said closed end. 110

8. A key including a cap inclosing a shutter having apertures therethrough, an indicator turning within the cap and having a plurality of faces bearing different characters arranged to register with the apertures in the shutter, the indicator turning on an axis parallel with the face of the key. 115

9. A key having a seat, a barrel mounted on the seat and having elongated guide slots therein, a cap inclosing the ring, an indicator shaft within the cap, and with its ends fitted in the guide slots, said shaft having a plurality of faces bearing different characters, a shutter having openings therethrough with which the characters register, a yielding journal bearing in which the shaft is supported, and shoulders on the 120 125 shaft.

shaft to engage the barrel to prevent end-wise displacement of the characters relative to the shutter.

10. A key having a seat, a barrel mounted thereon and having elongated guide slots therein, an indicator shaft in the cap with its ends fitted in the slots, and having a plurality of faces bearing different characters, and a yielding journal bearing to support 10 the shaft.

11. A key having a seat, a body or barrel mounted thereon and having elongated guide slots therein, an indicator shaft in the cap with its ends fitted in the slots, and having a plurality of faces bearing different characters, a cap inclosing the barrel and having an opening in alinement with the slots, through which opening one end of the shaft projects, a finger piece on said projecting end to turn the shaft, and a yielding journal bearing to support the shaft.

12. A key having a seat, a barrel mounted thereon and having elongated guide slots, an indicator shaft, the ends of which fit into 25 the slots, the shaft having a plurality of faces bearing different characters, a cap inclosing the barrel, and having a closed end to form the key face, a spring forming a yielding journal bearing to support the 30 shaft and to normally hold one or another of its faces against the closed end of the cap to prevent accidental turning of the shaft, and means to turn the shaft to cam it away from the closed end of the cap against 35 the tension of the spring.

13. A key having a seat, a barrel mounted thereon and having elongated guide slots, an indicator shaft, the ends of which fit into the slots, the shaft having a plurality of 40 faces bearing different characters, a cap inclosing the barrel, and having a closed end to form the key face, a spring forming a yielding journal bearing to support the shaft and to normally hold one or another 45 of its faces against the closed end of the cap to prevent accidental turning of the shaft, one end of the shaft extending through an elongated aperture in the cap, and a finger piece on said end to turn the shaft.

50 14. A key having a cap closed at one end to form a key face, an indicator shaft within the cap, and having a plurality of faces bearing different characters visible through the closed end of the cap, and a spring, the 55 ends of which are crossed to form a crotch engaging the shaft, effective to normally hold one or another of its faces squarely against the closed end of the cap to prevent accidental rotation of the shaft.

60 15. A key having a cap closed at one end to form a key face, an indicator shaft within

the cap, and having a plurality of faces bearing different characters visible through the closed end of the cap, and a spring bearing against the shaft, effective to normally hold one or another of its faces squarely against the closed end of the cap to prevent 65 accidental rotation of the shaft.

16. A key having a cap closed at one end to form a key face, an indicator shaft within 70 the cap and having a plurality of faces bearing different characters visible through the closed end of the cap, the shaft having a neck and a spring engaging the neck, and effective to normally hold one or another of 75 its faces squarely against the closed end of the cap to prevent accidental rotation of the shaft.

17. In a tabulating mechanism, a key comprising an indicator shaft having a plurality of faces bearing different characters, a yielding bearing therefor, and a body or barrel closed at one end to form a key face against which closed end one or another of 80 the indicator faces is pressed by the yielding bearing to hold it where adjusted.

18. In a tabulating mechanism, a key comprising an indicator shaft having a plurality of faces bearing different characters, a yielding bearing therefor, and a body or barrel closed at one end to form a key face, and against which closed end one or another 90 of the indicator faces is pressed by the yielding bearing to hold it in adjusted position, the barrel having slots in which the 95 ends of the shaft are guided toward and from the closed end when the indicator is rotated.

19. The combination with a key, of an indicator having a plurality of faces and 100 mounted within the key to turn over therewithin to expose any one of its several faces, and means extending to the exterior of the key to turn said indicator.

20. A key including an indicator mounted 105 on a resilient bearing and adapted to turn over within the key, the indicator having a plurality of faces, the uppermost one of which is yieldingly held against the face of the key from beneath by said bearing, to 110 prevent accidental turning of the indicator.

21. A key provided with a seat, a cap, a character-bearing device journaled in the cap, and turning on an axis substantially parallel with the face of the key, one end of 115 said device extending through an aperture in the cap to facilitate turning.
